Henry Whitney

United States Patent Office.

HENRY WHITNEY, OF EAST CAMBRIDGE, MASSACHUSETTS.

Design No. 3,067, dated June 2, 1868.

DESIGN FOR A TOILET-BOTTLE.

The Schedule referred to in these Letters Patent and making part of the same.

TO ALL PERSONS TO WHOM THESE PRESENTS MAY COME:

Be it known that I, HENRY WHITNEY, of East Cambridge, in the county of Middlesex, and State of Massachusetts, have invented or produced a new and ornamental Design for a Toilet-Bottle; and I do hereby declare the same to be represented in the accompanying drawings, of which—

Figure 1 is a side elevation, and

Figure 2 a bottom view of it.

Figure 3 is a top view of its neck.

The general form of the body part A of the bottle is that of a quadrilateral parallelopiped, with recessed and segmental corners *a a a a*. From this the neck B rises, and is shaped as represented.

Each side of the parallelopiped is cut with a series of hexagonal frusta *b b*, with triangular pyramids *c* between them, the whole being as shown in the drawings.

I claim the said design, substantially as described, and as shown in the accompanying drawings.

HENRY WHITNEY.
